UNITED STATES PATENT OFFICE

2,350,493

GUN LOADING MECHANISM

Cecil P. Caulkins, New London, Conn.

Application April 24, 1941, Serial No. 390,083

4 Claims.

(Cl. 89—45)

This invention relates to improvements in gun loading mechanisms, and its object is to provide a simple and inexpensive arrangement for expeditiously loading explosive charges onto projectors for same.

This invention is more especially adapted for loading depth charges onto the arbors used with Y guns of the type shown in U. S. Patent No. 1,311,780, issued to Andrew J. Stone, July 27, 1919, and in my copending application Serial No. 340,459, filed June 14, 1940, although it is not limited to such use. In guns of this type of the most commonly used size the charges weigh about four hundred and twenty pounds each and it has been necessary heretofore to have a gun crew of five or six men as these heavy charges had to be lifted onto the arbors and the loading operation took about two and a half minutes to perform. Such guns are now used, in some cases, on high speed patrol boats which must carry as small a crew as possible and where rapid firing is essential. By the use of this invention a gun crew of two men can load the gun in less than forty-five seconds.

I will describe an embodiment of this invention in the following specification and point out its novel features in appended claims.

Referring to the drawing,

Fig. 1 is an elevation of a Y gun, partly in section, with a loading mechanism which embodies my invention associated therewith;

Fig. 2 is a side elevation of the upper end of the gun shown in Fig. 1, drawn in section together with the charge elevator in its uppermost position;

Fig. 3 is a similar view of some of the parts shown in Fig. 2, with the charge and arbor turned around 90°;

Fig. 4 is a side elevation of a part of the loading mechanism, with the charge elevator in its lowermost position;

Fig. 5 is a plan view of the parts shown in Fig. 2, the view being taken from the direction indicated by the arrow in the latter figure; and

Fig. 6 is a plan view on a smaller scale of the lower end of the charge elevator and of certain parts associated with it.

10 designates a Y gun of the type shown in my aforesaid application, having a casing 11 which forms a firing chamber from which two barrels 12, 12 extend. 13, 13 designate sleeve slidably mounted on these barrels.

The arbors comprise tubular stems 20 which fit into the gun barrels. Their inner ends are closed, as at 21 (Fig. 1), and curved charge re-

ceiving trays 22 are fixed to the outer ends. The edges 23 of these trays are straight and normal to the axes of the stems 20. Affixed to the bottom of each tray is a locking clip 24 extending from one of its ends and having a hooked end 25. 26 is a similar clip extending from the other end of the tray and having a hooked end 27. This clip 26 is slidably mounted on the tray so that its hooked end may be moved to the position in which it is indicated by dotted lines at 27A in Fig. 3 when a charge 30 is first deposited on the tray in the position indicated at 30C in Fig. 3. The charges are of cylindrical form and have end flanges 31. After a charge has been deposited on a tray it is moved laterally to bring one of its end flanges under the hooked end 25 of the clip 24. Then the clip 26 is moved inwardly to bring its hooked end 27 over the flange 31 at the other end of the charge, after which the clip 26 is fastened in place by a thumb nut 28. The charge is thus locked firmly onto the tray.

20, 40 designate a pair of inclined guide rails secured to brackets 41 at their lower ends and to brackets 42 at their upper ends. 43 is a car slidably mounted on these guides. The car has a semi-cylindrical surface 44 for supporting a charge, a straight edge 45 parallel with the axis of the surface 44 and an end flange 46.

30 In Figs. 4 and 6 the car 43 is shown at the lower end of guide rails 40. In this position its surface 44 is aligned with charges 30A, 30B supported on rails 32 so that the charge 30A may be slid onto the car until its end abuts the flange. 35 This limits the movement of the charge onto the car and insures its proper lateral alignment with the tray 22 on the sleeves or stems 13.

The car is then raised by means of a cable 47 and a windlass 48 on bracket 42 to the position shown in Figs. 2 and 5, in which position it is held by a latch 49. An arbor has been placed in the gun barrel by hand, and if the edge 23 of its tray 22 is not in alignment with the edge 45 of the car 43, the first effect of this operation will be to adjust the arbor angularly to insure proper alignment. For example, if the proximate edge of the tray is initially in the position shown in dotted lines at 23A in Fig. 5, the arbor will be rotated until the edges 23 and 45 are aligned. Then a charge, such as that indicated at 30C in Fig. 2, is rolled out of the car 43 onto the tray 22 and attached to the latter in the manner previously described. The car may then be lowered and the gun fired and the operation repeated.

I intend no limitations other than those imposed by the appended claims.

What I claim is:

1. In combination with a gun barrel and an arbor having a cylindrical stem fitting the barrel and angularly rotatable therein and a charge receiving tray on the outer end of said stem, said tray having an edge offset from and normal to the axis of the stem, a car adapted to hold a cylindrical charge, said car having an edge parallel to the axis of the charge thereon, means for moving the car to said tray to bring said edge of the car into contact with said edge of the tray whereby the movement of the car is utilized to rotate the stem of the arbor to align said edges of the car and of the tray. 15

2. In combination with a gun barrel and an arbor having a cylindrical stem fitting the barrel and angularly rotatable therein and a charge receiving tray on the outer end of said stem, said tray having an edge offset from and normal to the axis of the stem and a fixed clip extending from one end of the tray having a hooked end adapted to engage a rim on one end of the charge, a slidable clip on the other end of the tray having a hooked end adapted to engage a rim on the other end of the charge, a car adapted to hold a cylindrical charge, said car having an edge parallel to the axis of the charge thereon, means for positioning the charge on the car to clear the hooked end of the fixed clip on the tray, means for moving the car to said tray to bring said edge of the car into contact with said edge of the tray whereby the movement of the car is utilized to rotate the stem of the arbor to align said edges of the car and of the tray. 20

3. In combination with a gun barrel and an

arbor having a cylindrical stem fitting the barrel and angularly rotatable therein and a charge receiving tray on the outer end of said stem, said tray having an edge offset from and normal to the axis of the stem, a car adapted to hold a cylindrical charge, said car having an edge parallel to the axis of the charge thereon, inclined guides arranged to direct the movement of the car, means for moving the car on said guides to said tray to bring said edge of the car into contact with said edge of the tray whereby the movement of the car is utilized to rotate the stem of the arbor to align said edges of the car and of the tray. 25

4. In combination with a gun barrel and an arbor having a cylindrical stem fitting the barrel and angularly rotatable therein and a charge receiving tray on the outer end of said stem, said tray having an edge offset from and normal to the axis of the stem and a fixed clip extending from one end of the tray having a hooked end adapted to engage a rim on one end of the charge, a slidable clip on the outer end of the tray having a hooked end adapted to engage a rim on the other end of the charge, a car adapted to hold a cylindrical charge, said car having an edge parallel to the axis of the charge thereon, means for positioning the charge on the car to clear the hooked end of the clip on the tray, inclined guides arranged to direct the movement of the car, means for moving the car on said guides to said tray to bring said edge of the car into contact with said edge of the tray whereby the movement of the car is utilized to rotate the stem of the arbor to align said edges of the car and of the tray. 30
